UNITED STATES PATENT OFFICE.

RICHARD T. FOLEY, OF NEW YORK, N. Y., ASSIGNOR TO TIMOTHY J. FOLEY AND
RICHARD T. FOLEY, OF NEW YORK, N. Y.

VALVE.

935,842.

Specification of Letters Patent.

Patented Oct. 5, 1909.

Application filed September 22, 1908. Serial No. 454,256.

To all whom it may concern:

Be it known that I, RICHARD T. FOLEY, a citizen of the United States, residing in the city of New York, borough of Manhattan, 5 in the county and State of New York, have invented a certain new and useful Improvement in Valves, of which the following is a specification.

The invention relates to valves and cocks 10 for controlling steam, water and other fluids, and the object of the invention is to provide a tightly closing valve, of few parts simply and economically constructed, easily operated and not liable to derangement and consequent leakage.

The invention consists in certain details 20 of construction and arrangements of parts by which the above objects are attained, to be hereinafter described and pointed out in the claims.

The accompanying drawings form a part 25 of this specification and show the invention as applied to an ordinary faucet or bib-cock.

Figure 1 is a side elevation. Fig. 2 is a 30 longitudinal vertical section, partly in elevation, and Fig. 3 is a plan view of a portion.

Similar letters of reference indicate the same parts in all the figures.

A is the body or casing of the faucet having the usual flange A¹ and screw-threaded 35 nipple A², and a diaphragm or partition A³ in the horizontal portion of which is a conical valve-seat A⁴. On the body of the faucet and forming part of the valve-casing is a vertical tubular neck A⁵ arranged 40 axially of the valve-seat, in which is loosely mounted a vertically movable valve-plug B having its lower end coned to match to the seat and carrying at the upper end a flanged head B¹ upon which pressure is exerted to 45 force it to its seat and by which it is lifted therefrom through a helical spring C inclosing the plug, abutting at its lower end against a guide A⁶ in the casing and at the upper end against the under face of the head.

The valve-plug is forced to its seat by a 50 nut or screw-cap D inclosing the upper end of the neck A⁵ and engaged therewith by internal threads matching to corresponding threads A⁷ on the exterior of the neck.

From the interior of the cap depends a 55 centrally arranged follower D¹ against which the head B¹ of the valve-plug impinges. By unscrewing the cap the plug is per-

mitted to rise from its seat through the expansive force of the spring C, and a reverse movement, through the action of the follower D¹, forces it to its seat in opposition to the lift of the spring.

The plug is guided by its head B¹ matching the interior of the neck at the upper end, and at the lower end by passing through the opening in the guide A⁶, the exterior of the latter also serves to center the spring.

At the upper end of the neck is an exterior flange or fixed collar A⁸ having an annular groove in which lies a packing ring E of suitable metal or other material, fitting closely to the interior face of the cap and serving to prevent the escape of any leakage around the plug to the screw-threads A⁷. The under face of this flange A⁸ also serves as a stop for the pins or screws F inserted through the wall of the cap after the parts have been assembled, and limits the upward movement of the cap, thus preventing the accidental removal of the latter.

It will be noted that the valve-plug is unattached and therefore free to adjust itself 80 to its seat, the rounded upper face of the head matching to the corresponding hollow in the under face of the follower permits slight changes in position of the plug in adjusting itself to the seat while insuring tight 85 contact therewith when in the closed condition and thus obviates the necessity of great accuracy in alinement of the plug relatively to the seat and other parts of the valve.

Surrounding the follower D¹ is a depending flange D² matching the interior of the neck and serving to guide the cap D in its rising and sinking movements. The cap is provided with radial arms D³ affording a 90 convenient turning means.

Modifications may be made within wide 95 limits in adapting the invention to meet the requirements of various conditions and forms of valves. Although the invention is shown and described as applied to a faucet for water or other fluids it will be understood that it will serve for steam or other purposes.

I claim:

1. In a valve, a casing with a partition 105 with valve seat and a guide in line therewith, a tubular neck and valve plug loosely movable and guided by said guide and fitted to said seat and having a flanged head, a spring around said plug abutting at its lower end 110 against said guide and at its upper end

against the flange of said head, a screw cap having threaded engagement with the said neck and provided with a centrally arranged follower impinging against the head of said valve, the outer end of said neck having an exterior flange with annular groove and a packing ring in said groove and fitting the interior wall of the cap.

2. In a valve, a casing with a partition 10 with valve seat and a guide in line therewith, a tubular neck and valve plug loosely movable and guided by said guide and fitted to said seat and having a flanged head, a spring around said plug abutting at its lower end 15 against said guide and at its upper end against the flange of said head, a screw cap having threaded engagement with the said neck and provided with a centrally arranged follower impinging against the head of said valve, the outer end of said neck having an exterior flange with annular groove, a packing ring in said groove and fitting the interior wall of the cap, and inwardly extending pins 20 on the annular portion of said cap adapted to engage said flange to prevent accidental removal of the cap.

3. In a valve, a loose valve-plug, a valve-seat therefor; a tubular neck in which said plug is guided, a spring tending to lift said 30 plug from said seat, a screw-cap inclosing the upper end of said neck and serving to force said plug to said seat in opposition to said spring, a flange on the exterior of said

neck having an annular groove therein, a packing ring in said groove, and pins on the 35 interior of said cap arranged to strike said flange and limit the upward movement of said cap said cap having a depending annular flange received within the upper end of said neck.

4. In a valve, a loose valve-plug having a head at the upper end, a valve-seat for the lower end, a tubular neck in which said plug is guided, a spring inclosing said plug, abutting beneath said head and tending to lift 45 said plug from said seat, a screw-cap engaged with threads on the exterior of said neck, a follower on the interior of said cap impinging against said head and serving to force said plug to said seat in opposition 50 to said spring, a flange on the exterior of said neck having an annular groove therein, a packing ring in said groove, a depending annular flange on said cap between the follower and the annular wall of the cap and 55 received within the upper end of the neck and pins on the interior of said cap arranged to strike said flange and limit the upward movement of said cap.

In testimony that I claim the invention 60 above set forth I affix my signature, in presence of two witnesses.

RICHARD T. FOLEY.
